US00D605590S

(12) **United States Design Patent**
Chen et al.

(10) **Patent No.:** US D605,590 S
(45) **Date of Patent:** ** Dec. 8, 2009

(54) **BLADE ASSEMBLY FOR POWER
GENERATOR**

(75) Inventors: **En-Feng Chen**, Taichung (TW);
Tzu-Yao Huang, Taichung (TW)

(73) Assignee: **Hiwin Mikrosystem Corp.**, Nantun
District, Taichung (TW)

(**) Term: **14 Years**

(21) Appl. No.: **29/314,748**

(22) Filed: **Apr. 24, 2009**

(51) **LOC (9) Cl.** **13-01**

(52) **U.S. Cl.** **D13/115**; D13/122

(58) **Field of Classification Search** D13/115,

(57) **CLAIM**

The ornamental design for a blade assembly for power generator, as shown and described.

DESCRIPTION

FIG. 1 is a perspective view of a blade assembly for power generator showing our new design thereof;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown represent unclaimed subject matter and form no part of the claimed design.

1 Claim, 5 Drawing Sheets
